UNITED STATES PATENT OFFICE.

GEORGE ARTHUR GORDON, OF TORONTO, ONTARIO, CANADA.

METAL SHINGLE.

1,153,619.

Specification of Letters Patent. Patented Sept. 14, 1915.

Application filed October 30, 1914. Serial No. 869,360.

To all whom it may concern:

Be it known that I, GEORGE ARTHUR GORDON, a subject of the King of Great Britain, and resident of the city of Toronto, county 5 of York, Province of Ontario, in the Dominion of Canada, have invented certain new and useful Improvements in Metal Shingles, as described in the following specification and illustrated in the accompanying drawings, that form part of the 10 same.

The principal objects of the present invention are, to eliminate the possibility of leakage at the joints or intersection of the 15 shingles, and to devise a form of metal shingle which will be very firmly secured in place.

The principal feature of the invention consists in the novel construction of the 20 shingle, whereby an intercepting gutter is arranged between the outer terminal edge of the overlapping shingle and the underlying terminal edge of the adjacent shingle, and whereby the shingles are securely fastened together by means of hook-shaped 25 fastening members.

In the drawings, Figure 1 is a perspective view showing portions of several inter-connecting shingles. Fig. 2 is a longitudinal 30 sectional view through the line *a—b* of Fig. 1. Fig. 3 is a cross sectional view through the line *c—d* of Fig. 1. Fig. 4 is a reduced plan view of an entire shingle constructed in accordance with this invention.

35 Like numerals of reference indicate corresponding parts in each figure.

Referring to the drawings, the shingle 1 is formed of a rectangular plate of sheet metal. This plate is shaped with a rib 2 40 of an inverted channel shape at one of its sides, which extends from the top edge 3 to the bottom edge 4.

45 5 and 6 are ribs spaced equidistant and formed of a similar shape to the rib 2, for the major portion of the depth of the shingle. At the upper end the ribs 5 and 6 are formed with a V-shaped channel 7 centrally located in the top and extending downwardly from the top edge 4 a distance 50 approximately equal to the depth of the weathering required in placing the shingles the one over the other in successive rows. The lower end 8 of the channel 7 is beveled or sloped upwardly and outwardly.

9 is a rib of substantially M shape in 55 cross section, the outer walls 10 thereof being sloped to correspond with the slope of the outer sides of the ribs 5 and 6 and of the same width apart and the inner walls forming a V-shaped channel 11 which extends from the top to the bottom edge of the shingle. The rib 9 is spaced from the rib 6 a distance equal to the spacing between the ribs 2 and 5 and 5 and 6 and the terminal edge 12 of the shingle extends outwardly a short 60 distance from the extreme outer wall 10 of the rib 9. This strip forms the nailing strip for securing the shingle in place.

65 13 are hook-shaped members secured to the ribs 5 and 6 at the lower end of the 70 V-shaped channel 7 and at one side thereof and 14 is a hook similar to the hooks 13 secured to the inner inverted V-shaped portion of the rib 9 and in transverse alinement with the hooks 13.

75 15 is a hole formed in the rib 2 in horizontal alinement with the shanks of the hook-shaped fastening members and adapted to receive the hook 14 of the next adjacent shingle when placed in position.

80 16 are holes formed in the ribs 2, 5 and 6 close to the bottom edge and in alinement with the hole 15 and hooks 13 respectively, these holes being adapted to receive the hook-shaped members 13 and 14 of the adjacent lower row of shingles when placed in position.

85 17 is a notch formed in the lower edge of the shingle at the bottom end of the rib 9, the upper edge of said notch being approximately in horizontal alinement with the upper sides of the holes 15. The holes 15 are so shaped that the under or lower half thereof is depressed and the upper half is arched upwardly so as to allow of the ready 95 insertion of the hook fasteners and fitting snugly around the shanks of the hook member. In placing these shingles, in laying the first row the outer shingle is first placed in position and nailed along the edge 12. The 100 rib 2 of the next shingle is then laid over the rib 9, the hook 14 being inserted into the hole 15, the rib 2 thus covering the rib 9 has its outer edge 18 fitting snugly against the wall 10 of the rib 9, and the flat top 19 105 stretches across the top of the V-shaped channel 11, the inner wall 20 fitting against the other outwardly sloping wall of the rib

9; a thoroughly weather proof joint is thus provided in that in the event of water beating under the outer edge 18 of the rib 2 it will be intercepted by the channel 11 and flow freely downwardly being discharged at the bottom.

In laying the second and succeeding courses of shingles, the joints are staggered or broken and the upper courses are slipped 13 into place so that the hook members 13 and 14 extend through the holes 16 at the bottom edge of the shingles and one of said hooks will fit into the corner of the notch 17. When the second course is thus laid the 15 lower ends of the ribs 2, 5 and 6 cover the V-shaped channels 7 formed and the ribs 9 fit into one of same, so that the said channel 7 forms a continuation of the channel 11 but owing to the notch 17 being cut in the bottom corner the bottom of the central V-shaped portion 11 does not interfere with the outwardly sloping lower edge 8 of the channel 7, consequently the shingle fits 20 snugly into place. The next succeeding 25 shingle then covers the rib 9 the same as in the manner described in laying the first course so that the joint in all cases presents the same appearance as the other ribs and all ribs are uniform and continuous extending 30 through the entire roof covering.

It will be seen that the weathering of the joint is very effective as in the case of the outer edge of any one of the ribs 2 being slightly raised or through extreme conditions of weather water is forced up under 35 the same, it will be intercepted by the V-shaped channel 11 and carried to the bottom of the shingle and in the case of the second and succeeding courses the water flowing down this channel flows into the lower end 40 8 of the channel 7 and is conducted to the upper surface of the under-lying shingle of the lower course, the water having free egress as the covering rib 2 is spaced above 45 the rib 2 of the lower course by the thickness of the metal of the rib 9.

The hook-shaped members are preferably inserted from the underside of the shingle and arranged at one side of the V-shaped 50 channel and either soldered, riveted or welded securely in place so that no leakage can occur and it will be readily seen that any leakage there is through the holes 15 and 16 is simply conducted outwardly through the 55 channels 7. The hook fastener members are shown as preferably arranged on the rib portion 5 of the shingle but it must be understood that they can be placed in other locations if desired.

60 With this construction of shingle it will be seen that as the outer rib 2 at one end is not provided with the center channel 7, it will be impossible to lay the shingles without breaking the joint, as the rib 9 65 with the channel extending from end to end

will not fit into place over the rib 2. Shingles so constructed are easily and quickly placed in position and firmly held against displacement by means of the hook-shaped fastening members of which any desirable 70 number may be used and as each shingle has an adequate nailing strip, the roof covering will be held securely against storm. The nailing strip is thoroughly weathered and protected as is each joint in the shingles by the arrangement of the open channel extending the full length of each joint between the shingles which channel is arranged to discharge into the short length 75 channels formed in the upper ends of the ribs 5 and 6 over whichever they may be located. It will be noted that the channels 7 are covered by the overlapping edge of the succeeding courses, consequently dirt will be prevented from lodging therein and 80 thus choking the channels and further the weather will be prevented from beating 85 under the joint.

What I claim as my invention is:—

1. A metal shingle having a plurality of 90 ribs of an inverted channel shape in cross section extending from top to bottom, one of the end ribs having a channel in the top extending the full length thereof and the intermediate rib having a channel in the top 95 extending partway down from the upper edge of the shingle.

2. A metal shingle having a plurality of 100 ribs of an inverted channel shape in cross section extending from top to bottom, one of the end ribs having a channel in the top extending the full length thereof the intermediate rib having a channel in the top extending partway down from the upper edge of 105 the shingle, hook-shaped fastening members secured to said shingles in sealed contact, and holes formed in said shingles adapted to receive the hook-shaped fastening members of the under-lying shingles.

3. A metal shingle having a plurality of 110 ribs of an inverted channel shape in cross section extending from top to bottom, the central rib having a channel formed in the top thereof at the upper end, one of the end ribs having a channel in the top extending 115 the full length thereof, holes formed in said shingles adapted to receive the hook-shaped fastening members of the underlying shingles, and a notch cut in the bottom edge of 120 said shingle at the lower end of the rib formed with the continuous channel, said notch being adapted to fit around the fastening hook on the lower course of shingles.

4. A metal shingle having a plurality of 125 ribs of an inverted channel shape in cross section, extending from top to bottom, the rib between the end ribs having a V-shaped channel formed in the center thereof at the upper end, the lower end of 130 said channel being sloped outwardly to

merge into the top of said rib, and one of the end ribs having a V-shaped channel in the center extending the full length thereof and adapted to coincide with the V-shaped channel at the upper end of the intermediate rib of underlying shingle of the next lower course.

Signed at the city of Toronto, county of York, Province of Ontario, in the Dominion of Canada, this 26th day of October 1914.

GEORGE ARTHUR GORDON.
